UNITED STATES PATENT OFFICE.

WALTER SCOTT SEAMAN, OF BEAVER, NORTH DAKOTA.

PIPE-GRAB.

No. 881,496.

Specification of Letters Patent. Patented March 10, 1908.

Application filed September 11, 1907. Serial No. 392,311.

To all whom it may concern:

Be it known that I, WALTER SCOTT SEAMAN, a citizen of the United States, residing at Beaver, in the county of Bowman and 5 State of North Dakota, have invented certain new and useful Improvements in Pipe-Grabs, of which the following is a specification.

My invention pertains to improvements in 10 pipe grabs, used in the drilling of wells to recover lost or displaced pipe sections, and has for its object to simplify the construction, increase the efficiency and to lessen the cost of production of devices of this type, and 15 to provide a thoroughly practical pipe grab.

With the above and other objects in view, my invention further consists in the novel 20 details of construction and combination of parts to be fully described in the following specification and pointed out in the claims.

Referring to the accompanying drawings forming a part of this specification, and wherein like characters of reference denote similar parts throughout the several views:—

25 Figure 1 is a central vertical sectional view, and Fig. 2, is a transverse section taken on line 2—2 of Fig. 1.

The invention contemplates a casing 1, preferably cylindrical in form, which has a 30 closed lower end and a cap 2, of any desired type, removably fitted to its upper end. At a point adjacent the bottom of the casing a stationary plate 3, is secured by means of screws or the like.

35 4, designates an operating rod, the upper end of which is passed through an opening provided therefor in cap 2, and the lower end of which is threaded and received in a threaded opening formed therefor in plate 3. 40 A hand wheel 5, is secured to the upper end of rod 4.

Secured to the upper face of plate 3, are the 45 feet 6, of the jaw members 7, the latter embodying vertically arranged shanks which terminate in outwardly turned ends 8, having serrated faces 9, which are adapted to engage the inner face of the pipe 10, as depicted in the drawings. To accommodate the ends 8, of the jaw members, the casing 1, 50 is formed with slots 11, through which ends 8, project. The jaw members 7, are formed of spring-like material so that the serrated faces of the same may move outwardly and inwardly with respect to casing 1, and their 55 bases 6. To provide for this movement as well as to cause the serrated faces to firmly

grip the pipe during the removal of the latter, I employ an abutment 12, which is formed to occupy the interior of casing 1, and to have a central longitudinal opening through which operating rods 4, freely passes. Collars 13 and 14, are firmly sustained on rod 4, and engages the opposite ends of abutment 12, to thereby prevent longitudinal movement of the abutment with respect to rod 4. The 60 abutment is formed with two opposite vertical slots 15, which receive the jaw members therein, these slots being of such width as to freely receive the upper ends of the jaw members. The bottoms of the slots are formed 65 with cam faces 16, which bear against the rear of the outturned ends 8, of the jaw members 7, and thus when the abutment is lowered with respect to the jaw members, the ends 8, of the latter will be gradually forced 70 outwardly into firm gripping engagement 75 with the pipe 10.

To assist the jaws in their function of gripping the pipe during the removal of the latter, I provide a compressible and expandable 80 washer 17, of a size which when forced into pipe 10, will expand and grip the pipe to thereby further assist the action of jaws 10. This washer bears against the bottom of casing 1, and is removably secured thereto by 85 means of a metal washer 18, and screw 19, which latter is in threaded engagement with the casing bottom.

The operation will be understood from the above; rotary movement being communicated 90 to rod 4, the latter will be raised or lowered due to its threaded connection with stationary plate 3, carrying abutment 12, therewith. Since abutment 12, freely receives rod 4, the latter will not communicate 95 its rotary motion thereto. By adjusting the position of the abutment with respect to the jaw members the latter may be caused to grip the pipe being removed as may be found necessary or desirable. Washer 17, serves 100 to also properly center the lower end of casing 1, and assists in enabling the device to obtain further gripping action on the pipe in addition to that secured by the jaw members.

What I claim is:—

1. A pipe grab embodying a casing, jaw members carried by said casing and projecting beyond the sides thereof, and an adjustable abutment in said casing bearing against said jaw members.

2. A pipe grab embodying a casing, a plate stationary therein and having a threaded

105

110

opening, jaw members supported at their lower ends from said plate and having their upper ends serrated and projecting beyond the casing sides, an operating rod having a 5 threaded part engaging said threaded opening of the plate, and an abutment loosely mounted on said rod means to cause said abutment to partake of the longitudinal movement of said rod, said abutment having 10 cam faces which bear against said jaw members and force the same beyond said casing sides.

3. A pipe grab embodying a casing, a flexible washer on the bottom end of the casing 15 projecting beyond the casing sides, means to clamp said washer to said casing end, and means at the opposite end of the casing to engage the pipe.

4. A pipe grab embodying a casing, an expandible washer secured to the exterior of the bottom of said casing, jaw members secured 20 at their lower ends on the casing interior and at their upper ends projecting beyond the exterior of the casing, and means for impelling 25 said upper ends of the jaw members outwardly.

5. A pipe grab embodying a casing, an expandible washer secured to the lower end of the casing and projecting beyond the sides 30 thereof, jaw members carried by said casing and having gripping faces which project beyond the casing sides at the upper portion of the casing, and means to move said gripping faces outwardly beyond the casing sides.

35 6. A pipe grab embodying a casing, a flexible washer immovably carried on the bottom thereof to engage the pipe, means carried by the casing adjacent the upper portion thereof to also engage the pipe, and means to actuate 40 said last named means.

7. A pipe grab embodying a casing, a plate rigidly secured therein and having a threaded opening, jaw members having gripping faces projecting beyond the casing sides, a rod threaded at one end into said opening of the 45 plate, and means on the rod to engage said jaw members and move the gripping faces thereof outwardly.

8. A pipe grab embodying a casing, a plate therein having a threaded opening, vertically 50 disposed jaw members secured at their lower ends to said plate and having right angular upper ends which project beyond the casing sides and terminate in gripping faces, an operating rod having a threaded part engaging 55 said threaded opening of said plate an abutment freely carried by said rod and having vertical slots therein in which the upper ends of said jaw members extend, cam faces carried by said abutment to engage the rear portions of said right angular ends of the jaw members, and means on the rod to engage said abutment and prevent longitudinal movement thereof on said rod.

9. A pipe grab embodying jaw members, 60 and an operating rod therefor carrying means to engage said jaw members and impel the same outwardly, said means being loosely mounted on said rod, means whereby said means will move with said rod and means 70 whereby when said rod is rotated the same will be advanced so as to advance said means for actuating the jaw members.

In testimony whereof I affix my signature, in presence of two witnesses.

WALTER SCOTT SEAMAN.
